UNITED STATES PATENT OFFICE

REINHOLD A. NORLING, OF AURORA, ILLINOIS, ASSIGNOR TO INDEPENDENT PNEUMATIC TOOL CO., OF CHICAGO, ILLINOIS, A CORPORATION OF DELAWARE

VALVE CONSTRUCTION FOR PNEUMATIC TOOLS

Application filed April 6, 1931. Serial No. 528,044.

This invention relates to a plate valve construction for pneumatic hammers and like tools.

Plate valve devices, as heretofore employed, have been so designed and constructed as to require a lapped or ground fit between the peripheral edge of the valve member and the chamber in which it has lateral shifting movement to prevent leakage of live air past the valve member in the operation of the tool. With the valve member shifting repeatedly in the operation of the tool, the rubbing action of the peripheral edge or surface of the valve member against the adjacent surface of the valve chamber soon wears the valve member and permits leakage which causes the tool to lose power in proportion to the amount of the wear. To rectify the leakage, either the block or the valve member, or both, have to be replaced, because with a plate type of valve, there is no way of taking up the wear. If one of the parts only is replaced, the standard is changed. For instance, if the valve member is to be changed, an oversize valve member need be used and the block either lapped or ground in order to obtain the proper contact relation between the edge of the valve member and the block. This requires the services of a skilled mechanic, which services are not always available by the user of the tool. The lapped or ground joint between the edge of the valve member and the block is required because the ports controlled by the valve member are at or sufficiently close to the edge or periphery of the valve member to leak around the edge of the valve member when such edge becomes worn. Furthermore, the valve member, as heretofore employed, is in the form of a relatively thin plate or disc so as to be light in weight for ease and rapidity of shifting and being thin does not have sufficient body to stand a great deal of wear at its peripheral edge where it must retain contact with the block to prevent the leakage referred to.

In accordance with my invention, I offset the ports in the block as controlled by the valve member well within the peripheral edge of the valve member and thus do not require such edge to have a lapped fit with the block,

to prevent leakage as heretofore. Consequently, any wear at the peripheral edge of the valve member, either on the latter or on the block will not permit leakage or cause the tool to lose power. Moreover, there is no appreciable amount of friction developed between the edge of the valve member and the block to retard the rapid shifting thereof, and as a result the tool operates with greater speed.

In accordance with my invention, the opposite side surfaces or faces of the valve member and the opposed surfaces or faces of the block, when in contact, are relied upon to prevent leakage past the valve member instead of the edge of the valve member as heretofore. Consequently, any wear or pitting of such surfaces can be readily eliminated by a grinding or lapping operation. With such surfaces made perfectly straight or flat, lapping of the same can be done in a few minutes' time by merely removing the valve parts from the tool and rubbing them on a surface plate with a suitable lapping compound. This will restore the valve device to proper working order without being required to replace either part or change or alter their original outside diameters.

A further object of my invention is to so arrange the ports in the block, as controlled by the valve member, adjacent the peripheral edge thereof, so that the central or intermediate portions of the valve member on the opposite sides thereof will not close such ports and may thus be employed as the pressure areas for shifting the valve. These areas are preferably formed by recesses or cavities in the opposite sides of the valve member so as to be open to live air pressure when the valve member is in contact with the block. These recesses or cavities are preferably centrally arranged in the valve member and have substantially the same diameter so that the valve member will function regardless of which side of the valve is uppermost or whether the center inlet ports in the upper or lower members of the block are of different sizes.

By my invention, the valve device is simplified and cheap to manufacture and install.

The only accuracy required is that the faces of the block and the valve member be straight, that is, flat. Moreover, the hammer or tool is shorter and consequently lighter in weight.

5 The invention consists further in the matters hereinafter described and claimed.

In the accompanying drawings:—

10 Fig. 1 is a longitudinal sectional view through a pneumatic hammer equipped with a valve device constructed in accordance with my invention;

15 Figs. 2, 3, 4, 5, 6, 7 and 8 are transverse sectional views taken on lines 2—2, 3—3, 4—4, 5—5, 6—6, 7—7, and 8—8, respectively, of Fig. 1; and

20 Figs. 9, 10, 11, and 12 are longitudinal sectional views taken on lines 9—9, 10—10, 11—11, and 12—12, respectively, of Fig. 4.

25 In the drawings, 1 indicates the barrel of the tool forming a cylinder, in which is reciprocated a piston 2 for delivering blows to the chisel or other working element 3 at the forward end of the barrel. The handle 4 at the opposite end of the barrel is provided with a tubular extension 5 which fits over the inner end of the barrel and has screw threaded connection therewith as shown. Compressed air, the motive fluid employed for operating the tool, is supplied to the barrel for reciprocating the piston 2 therein through a passage 6 in the handle 4, the latter having a manually operable valve 7 for controlling the flow of air through said passage as in tools of the character herein shown.

30 The valve device of my invention comprises a pair of upper and lower blocks 8, 9, preferably circular in form and fitting within the bore of the tubular extension 5 of the handle beyond the inner end of the barrel 1, as shown in Fig. 1. A flat ring 10 of substantially the same outside diameter as the blocks 8, 9 is located between them and spaces the blocks apart to provide an annular chamber 11 within the inner circumference of the ring. A valve member 12 in the form of a substantially flat circular plate is located in the chamber 11 and has lateral shifting movement therein to control the admission of live air to the opposite ends of the barrel. The blocks 8, 9 are provided with a number of radial recesses milled or formed in their outer faces. The recesses in the block 8 are shown in Figs. 2 and 12, and are designated by 13, 13, and 14, respectively. The recesses in the block 9 are shown in Figs. 4 and 11, and are designated by 15, 15 and 16, respectively. With the recesses in the blocks opening through the outer faces of the same, I provide cover plates 17, 18 therefor, as shown in Figs. 1, 11, and 12. The blocks, plates, and ring are preferably made co-extensive, and these parts are held 55 together in their superimposed relation by

dowel pins 19, 19, which as shown in Fig. 1, pass through the various parts of the valve device, exterior of the valve member 12.

5 The valve device in its assembled relation is situated against the inner end of the barrel 1, and is held in place by the handle 4 through an annular shoulder 20 therein bearing against the upper cover plate 17 as shown. The openings in the upper cover plate 17 for the dowel pins 19 are counter-sunk on their inner sides to form seats for the upper ends of the pins. The opposite or lower ends of the pins fit in the upper ends of the longitudinal passages 21, 21, in the barrel 1, said passages being made large enough at their upper ends to receive the pins, and to provide shoulders for the lower ends of the pins to hold them in place as shown in Fig. 1. The dowel pins fit loosely in the holes provided therefor in the valve device, so that the parts 25 may be separately removed when the handle 4 is unscrewed from the barrel. When the parts are in the tool, the handle on being screwed onto the barrel clamps the valve device tightly against the same. The cover plates 17, 18, may be fixed to their respective blocks by rivets 19^a, 19^a, as shown in Fig. 10.

35 As shown in Fig. 9, the radial recesses 14, 16 in the upper and lower blocks 8, 9 are connected at the opposite sides of the valve device through ports or passages 22, 22, in the ring 10. Block 8 is provided with a center port 23, which connects passage 14 with the valve chamber 11. Block 9 has a similar central port 24 connecting recess 16 with valve chamber 11. Upper cover plate 17 is provided with a center port 25 connecting recess 14 with a chamber 26 formed in the portion of the handle inside of the clamping shoulder 20. Chamber 26 connects directly 40 with the main inlet passage 6 in the handle, as shown in Fig. 9.

45 As shown in Figs. 2 and 4, blocks 8 and 9 each have a single recess 14, 16, respectively, which recess extends diametrically across its block and has portions on opposite sides of its associated center port 23, 24, as the case may be. The other radial recesses 13 and 15 in the respective blocks are much shorter than the associated recesses 14 and 16 and are arranged in sets or groups on opposite sides thereof. In the form of device shown, there are four of these short recesses in each block, two on each side of the associated recess 14 or 16, and all spaced about the 50 blocks so as to supply motive fluid to the barrel at various points about the circumference thereof.

55 The inner end of each recess 13, as shown in Figs. 2 and 12, is over the valve chamber 11 well inside of the inner circumference of the ring 10 and is connected with said chamber by one or more ports 27, 27, extending through the portion of the block 8 between the chamber and the recess 13. The inner end of 60

each recess 15, as shown in Figs. 4 and 11, is similarly disposed with respect to the chamber 11 and is connected therewith by a port 28 in the portion of the block 9 between the chamber and the recess 15. The outer end of each recess 15 is connected to a longitudinal passage 29 in the barrel 1 by a port 30 in the lower cover plate 18 as shown in Fig. 11. Passages 29 connect through ports 31, 31 with the forward end of the barrel, that is, the cylinder as provided by the barrel for the piston 2. The forward end of the piston is tapered so as not to cover ports 31 when the piston is at the forward end of the barrel and in contact with the working tool 3. The outer end of each recess 13 is connected with the inner end of the cylinder through ports 32, 33, 34 and 35 in the ring 10, lower block 9, cover plate 18, and barrel 1, respectively, as shown in Fig. 12.

The opposite side faces of the valve member 12 are centrally recessed, as at 36, 37, so that when the valve member is against the inner surface of either block 8 or 9, the center ports 23, 24 in the blocks will not be closed by the valve member. The marginal portion of the valve member will, however, alternately open and close the ports 27, 28, in the lateral shifting of the valve member into and out of contact with the blocks.

The operation of the tool is as follows: Opening valve 7 in handle 4, admits compressed air from the supply to chamber 26 through passage 6. From chamber 26, the compressed air enters recess 14 in the upper block 8 through center port 25 and into valve chamber 11 on the top side of the valve member 12 through center port 33. From recess 14, the compressed air flows into recess 16 in the lower block 9 through ports 22 and enters chamber 11 on the lower side of the valve member 12 through the center port 24. By this arrangement, there is a constant pressure at all times on two sides of the valve member 12. In starting the operation of the tool, the piston 2 being at the outer end of the barrel 1 and the valve member 12 resting on the lower block 9, as shown in Fig. 1, the full pressure is in the cavity 37 in the under side of the valve member. Ports 27, 27, in the upper block 8 are uncovered by the valve member 12, as shown in Fig. 12, and are open to the exhaust through ports 38, 38, in the handle section 5 of the tool by way of ports 32, 33, 34, 35, passages 21, and ports 39, 40 thereof, as shown in Fig. 1. These ports being considerably larger in area than the center port 23 in the upper block 8, the pressure on the upper side of the valve member 12 is reduced, allowing the valve member 12 to shift upward against the upper block 8 to close the exhaust through ports 27, 27, as shown in Fig. 11. This opens ports 28 in the lower block 9 and allows live air to flow to the forward end of the barrel (to

drive the piston 2 rearward) through recesses 15, ports 30, passages 29, and ports 31, as shown in Fig. 11. As soon as the piston in its rearward movement uncovers ports 41, the portion of the cylinder in the barrel forward of the piston is open to the atmosphere through passages 42, 42 in the barrel, which passages by ports 43, 43, connect with the space about the valve blocks as served by the main exhaust ports 38. The pressure is thus reduced on the under side of the valve member 12. Ports and passages 28, 15, 30, 29 and 31, being considerably larger in area than center port 24, and the full pressure being on top of the valve member 12 in the cavity 36, the valve member will shift toward the lower block 9 to close ports 28 therein. By this time the piston 2 will have reached the inner end of the cylinder, as shown in Fig. 12, and the ports 27, 27, being open, will admit live air to the rear end of the cylinder to drive the piston forward. As soon as the piston in its forward movement uncovers exhaust ports 44, the pressure on the top of the valve member 12 will be reduced and the full pressure being on the under side of the valve, the latter will again shift upward or rearward to close ports 27 and the inlet ports at the front end of the cylinder will be again opened to drive the piston rearward to repeat the cycle of operations. It will be observed that the piston in its movement controls the exhaust from the barrel, the valve member 12 serving at all times as an inlet control.

With the ports 27, 28 offset inward from the peripheral edge of the valve member 12, the annular portion of said member may be employed to open and close such ports, and thus the peripheral edge of the valve member need not fit against the inner circumference of the ring 10 to prevent leakage around the valve member, as heretofore. Any wear at the peripheral edge of the valve member will not cause the tool to lose power, as the flat side surfaces of the valve member where they contact with the opposed flat surfaces of the blocks about the ports 27, 28, are employed to prevent leakage past the valve. As these surfaces may be lapped, any wear or pitting thereof may be removed without replacing any of the parts. The valve member 12 not requiring a tight fit in the chamber 11 will have a faster movement, thereby increasing the speed of the tool. The recesses or cavities 36, 37, in the opposite sides of the valve member provide pressure areas for shifting the valve.

An exhaust deflector 45 is arranged on the exterior of the tool over the main exhaust ports 38.

The details of construction and arrangement of parts shown and described may be variously changed and modified without departing from the spirit and scope of my in-

vention, except as pointed out in the appended claim.

I claim as my invention:

In a fluid actuated hammer, the combination of a cylinder having a free exhaust, a hammer piston in the cylinder controlling said exhaust, a valve device for said cylinder for controlling the admission of pressure fluid to the opposite ends of the same, said valve device having a valve chamber, inlet and outlet ports opening into the chamber on opposite sides thereof, there being a single centrally disposed inlet port and a plurality of outlet ports on each side of the chamber, and a plate valve member laterally shiftable in said chamber for alternately opening and closing said outlet ports, said valve member having central recesses on opposite sides opposite the inlet ports and surrounding the same to prevent closing of the inlet ports by the valve member and to provide enlarged pressure areas for shifting the valve member, said outlet ports being disposed exterior of the recesses and located between the same and the periphery of the valve member.

In testimony whereof I affix my signature.

REINHOLD A. NORLING.
